United States Patent Office.

W. N. MOORE, OF NEE NAH, WISCONSIN.

Design No. 3,137, dated July 28, 1868.

DESIGN FOR A STOVE.

The Schedule referred to in these Letters Patent and making part of the same.

TO ALL WHOM IT MAY CONCERN:

Be it known that I, W. N. MOORE, of the village of Neenah, county of Winnebago, and State of Wisconsin, have originated and designed a new Pattern for a Heating-Stove, designated as the "Emperor," of which the following is a full, clear, and exact description, reference being had to the accompanying engraving in perspective, making part of this specification, wherein—

The top of the said stove projects over the ends and sides thereof, with rounded corners and moulded edge, the ends projecting in an elliptical segment.

The sides and back end of the stove project with a convex surfaced panel, surrounded with a moulding, in ovolو form, rounded to the corners, top, and base.

The centres of the sides and back end are relieved with plane oval-sunk panels in numbers according to the size and length of the stove.

The ends of the stove are shaped to correspond with the elliptical form of the top.

The base projects from the sides and ends, and is relieved with mouldings.

The door is rounded in a convex form, to correspond with the general design of the stove, and is relieved by a panel, with a star in *basso-relievo* in the centre.

The hearth springs from the bottom of the base of the stove, curving down and graduating into a horizontal plane below the plane of the base with corners rounded, the end projecting in an elliptical segment corresponding with the end of the top and body of the stove.

The legs are of an irregular form, largest at the top, surrounded with a fillet traced on the face of the edge. The upper half is a convex in form, relieved by a circular-sunk panel, with a star in *basso-relievo* in the centre. The lower half of the leg is narrower, nearly uniform as to width, the centre rounding out, and relieved with a half ball on the surface, in *basso-relievo*, near the bottom, all of which, with the more specific forms of the details, will more fully appear by reference to the accompanying engraving.

What I claim as my invention, and desire to secure by Letters Patent, is—

The design for stoves herein set forth and shown.
